UNITED STATES PATENT OFFICE.

PAUL KOSACK, OF GRAND ISLAND, NEBRASKA.

PLASTIC REINFORCED BUILDING CONSTRUCTION.

Application filed July 23, 1927. Serial No. 207,861.

The invention relates to plastic reinforced building construction and particularly walls, and has for its object to provide a wall comprising inner and outer members formed 5 from superimposed plastic blocks, plates interposed between the courses of the plastic blocks and having upwardly and downwardly extending flanges and tie rods connecting the plates carried by the inner and 10 outer wall sections, thereby positively tying the wall sections together and allowing plastic material to be poured between the wall sections.

A further object is to provide the plates 15 with T-shaped recesses for the reception of vertically disposed T bars engaging the inner sides of the wall sections.

A further object is to provide the plates with inwardly extending members having 20 downwardly extending flanges, which flanges frictionally engage the inner sides of the wall sections and grip the same incident to spring action of the plates.

With the above and other objects in view 25 the invention resides in the combination and arrangement of parts as hereinafter set forth, shown in the drawing, described and claimed, it being understood that changes in the precise embodiment of the invention may 30 be made within the scope of what is claimed without departing from the spirit of the invention.

In the drawings:

Figure 1 is a top plan view of a section of 35 wall formed in accordance with the invention.

Figure 2 is a top plan view of a plate used in connection with studding to which laths are to be secured.

40 Figure 3 is a top plan view of one of the plates carried by the straight portion of the outer wall section.

Figure 4 is a side elevation of the member shown in Figure 2.

45 Figure 5 is a side elevation of the plates shown in Figure 3.

Figure 6 is an enlarged top plan view of the plate carried by the corner of the inner wall section.

50 Figure 7 is a transverse sectional view taken on line 7—7 of Figure 2.

Figure 8 is a view in elevation of a portion of a wall, part being shown in section to better illustrate the structure.

55 Figure 9 is a plan view of the corner plate of the outer wall.

Figure 10 is a sectional view through the plate taken on line 10—10 of Figure 9.

Referring to the drawings, the numeral 1 designates the inside wall and 2 the outside 60 wall which are in spaced relation. The inner and outer walls 1 and 2 are formed from a plurality of superimposed plastic blocks 3, which may be provided with channels 4 if desired, however this is not essential. 65

The inner and outer walls 1 and 2 are tied together by means of plates 5, 6 and 7, and which plates are horizontally disposed and provided with upwardly and downwardly extending flanges 8 which engage the outer 70 sides of the blocks 3 and engage the outer faces of said blocks. Plates 5, 6 and 7 are horizontally disposed and extend inwardly into the chamber 9 between the wall sections and are provided with flanges 10 which extend downwardly and have their inner edges 75 11 in close binding engagement with the inner sides of the blocks. The close binding engagement is obtained by providing the plates with a spring action as clearly shown in Figure 5, whereby when the plates are placed in position the inner ends are flexed upwardly to allow the blocks to be received between the flanges 8 and the ends 11 of the flanges 10, and upon release of the outer ends of the plates, there will be a gripping action. The plates 5, 6 and 7 are provided with T-shaped 80 recesses 12 for the reception of vertical T bars 13, which engage the inner sides of the wall sections, therefore it will be seen that the wall sections are positively tied to the T bars. The plates 5, 6 and 7 are provided with a plurality of apertures 14 which receive the hooked 85 ends of tie rods 15, and which tie rods rigidly and positively anchor the wall sections together and maintain said wall sections in proper spaced relation at all times. Disposed on the upper side of the wall is a roof bed 16, which is anchored to the wall by means of a headed bolt 17, the head 18 of which is imbedded in the plastic material 19, poured between the wall sections, therefore it will be 90 seen that the roof bed is positively anchored and when the plastic material 19 is in place, a solid rigid wall is formed. Where it is desired to attach studding 20 to the inner side of the inner wall section 1 for applying lathing the angle brackets 21 are used, said brackets being of the form shown in Figures 2 and 3 and have upwardly and downwardly extending flanges 22.

From the above it will be seen that a wall

construction is provided, which is simple, will allow a wall to be easily and quickly formed, and one wherein concrete blocks are used for forming the outer and inner walls, and which outer and inner walls are positively tied together by means of the plates and tie rods, thereby allowing the forming of a solid wall by the pouring of a plastic between the wall sections.

10. The invention having been set forth what is claimed as new and useful is:—

1. A wall construction comprising inner and outer wall sections having a chamber therebetween, plates extending between 15 courses of blocks of the wall sections, said plates having angularly disposed flanges engaging the outer faces of the blocks, said plates extending inwardly into the chamber, downwardly extending flanges carried by 20 the plates within the chamber and engaging the inner sides of the blocks at an angle thereto, tie rods connecting the plates of the inner

and outer wall sections, said plates having recesses therein for the reception of vertically disposed members engaging the inner sides of 25 the wall sections.

2. A wall construction comprising inner and outer wall sections in spaced relation and formed from courses of superimposed blocks, plates between said courses of blocks, said plates having upwardly and downwardly extending flanges engaging the outer faces of blocks of adjacent courses, T bars extending vertically in engagement with the inner sides 30 of the wall sections and disposed in T-shaped recesses in the plates, the plates extending inwardly and provided with downwardly extending flanges, said flanges having their inner ends in engagement with the inner sides 35 of the wall sections, and tie rods connecting 40 said plates.

In testimony whereof I hereunto affix my signature.

PAUL KOSACK.
